US0D1014782S

(12) **United States Design Patent** (10) **Patent No.:** **US D1,014,782 S**
(45) **Date of Patent:** **** Feb. 13, 2024**

(54) **PARTITION**

(71) Applicant: **STEELCASE INC.**, Grand Rapids, MI (US)

(72) Inventors: **Mark McKenna**, East Grand Rapids, MI (US); **Brett Willink**, Grand Rapids, MI (US); **Hyun Yoo**, Grand Rapids, MI (US); **Nathan McCaughan**, Grand Haven, MI (US); **Cyril Joseph Mayne**, Grand Rapids, MI (US)

(73) Assignee: **Steelcase Inc.**, Grand Rapids, MI (US)

(**) Term: **15 Years**

(21) Appl. No.: **29/875,689**

(22) Filed: **May 9, 2023**

Related U.S. Application Data

(63) Continuation of application No. 29/765,520, filed on Jan. 8, 2021, now Pat. No. Des. 990,707.

(57) **CLAIM**

We claim the ornamental design for a partition, as shown and described.

DESCRIPTION

FIG. 1 is a top front/right perspective view of a first embodiment of a partition;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a top front/right perspective view of a second embodiment of a partition;

FIG. 9 is a front elevation view thereof;

FIG. 10 is a rear elevation view thereof;

FIG. 11 is a right side elevation view thereof;

FIG. 12 is a left side elevation view thereof;

FIG. 13 is a top plan view thereof; and,

FIG. 14 is a bottom plan view thereof.

The broken lines of FIGS. 1-7 are for the purpose of illustrating portions of the partition that form no part of the claimed design. The broken lines in FIGS. 8-14 are for the purpose of illustrating boundaries and portions of the partition that form no part of the claimed design.

1 Claim, 14 Drawing Sheets
